UNITED STATES PATENT OFFICE

ALFRED M. STOCKMAN, OF IRVINGTON, NEW JERSEY

DISPLAY STAND

Application filed February 15, 1928. Serial No. 254,381.

This invention relates to display stands and more particularly of the easel type.

The objects of the invention are to provide a display stand which will readily lie flat when not in use and may be quickly and easily placed in service; to utilize an article to be displayed as means for retaining the display stand in operative position; to secure simplicity of construction and operation, and to obtain other advantages and results as may be brought out in the following description.

Referring to the accompanying drawing, in which like numerals of reference indicate similar parts throughout the several views;

Figure 1 is a perspective view of my improved display stand in use;

Figure 2 is a central vertical section of the same;

Figure 3 is a similar central vertical section showing a modified construction; and

Figure 4 is a face view of said modified construction showing the same laid out flat.

In the specific embodiment of the invention illustrated in said drawing, the reference

numeral 1 indicates the body portion of the display stand which may be of suitable size and shape for both mounting a package 2 which is to be displayed and which will fur-

nish space for advertising the product and also a sufficient amount of material so as to provide a proper degree of strength of said body portion. If found desirable, wings 3, 3

may be provided at each side of said body portion which can be bent backwardly at an

angle to the plane of the body portion for purpose of appearance, re-enforcement and for increased advertising space. These wings

may be properly shaped to meet all of these requirements, and may also be arranged to rest at their lower ends upon the same sur-

face with the lower end of the body portion and at the same time permit the body portion to tilt backwardly at a moderate angle.

The central part of the body portion is pro-

vided with an opening 4 of substantially the circumferential dimensions of the box or

other article 2 which is to be displayed. In

making the said opening 4, the material

forming the body portion is sheared on three

sides of a rectangular outline and is scored as at 5 at the fourth side so as to enable the material of the body portion defined by the sheared and scored lines to form a tongue 6 which can be bent rearwardly on the scored line 5 to form a prop for the body portion. Preferably the scored edge is the one adjacent the bottom of the body portion as clearly shown in the drawing. Accordingly, the container 2 being displayed can be inserted in the opening 4 and it will then rest upon the hinged end of the tongue 6, thereby preventing the tongue from swinging back on the scored line or hinging 5. This construction accordingly enables me to construct a display stand of cardboard and utilize the article being displayed as a means for retaining the prop in operative position.

Preferably the box or article being displayed is frictionally held in position by means of a tongue 7 at one edge of the opening 4. In the present showing, I have located this tongue 7 at the top of the said opening, and form the same by extending the side shearing for the opening a little beyond the required height for the opening relying upon the resiliency of the material forming the body portion to actuate said tongue into frictional contact with the article being displayed. It is not to be understood, therefore, that I confine myself to a rectangular shape, as it is within the scope of the present invention to vary the shape of the opening to correspond to the particular article being displayed.

If found desirable or necessary, I may also stamp out a supplemental tongue 8 from the prop 6 as shown in Figures 3 and 4, this supplemental tongue 8 being free to swing out of the plane of said tongue behind the article being displayed and retain said article within the opening 4 of the body portion. While this supplemental tongue 8 is shown in the drawing as utilized in the device having a friction tongue 7 to engage the article, it will be understood that I do not confine myself to use of both tongues 7 and 8 at the same time. It is also to be understood that I may glue or otherwise secure on the back of the material forming the display

stand suitable fabric or other re-enforcements 9 at any or all of the lines of bending of the material. This use of fabric re-enforcement will lengthen the life of the display stand, adding to the durability at the points of greatest wear due to flexing of the material. I also deem it within the scope of the present invention to make other detail changes and modifications without departing from the spirit or scope of the present invention, and I do not wish to be understood as limiting myself to the exact construction shown, except as set forth in the following claims when construed in the light of the prior art.

Having thus described my invention, I claim:—

1. A display stand comprising a body portion having upstanding portions angularly disposed with respect to a transverse plane so as to strengthen said body portion for supporting the weight of an article to be displayed, said body portion having an opening therein for reception of said article and support thereof on an upstanding portion of said opening and a tongue bent from said opening at one edge of the same, said tongue acting as a prop for the display stand and retained in its propping relationship by positioning of the article to be displayed in said opening.

2. A display stand comprising a body portion having upstanding portions angularly disposed with respect to a transverse plane so as to strengthen said body portion for supporting the weight of an article to be displayed, said body portion having an opening therein for reception of said article and support thereof on an upstanding portion of said opening, a tongue bent from said opening at one edge of the same, said tongue acting as a prop for the display stand and retained in its propping relationship by positioning of the article to be displayed in said opening, and means for retaining the article to be displayed in said opening.

3. A display stand comprising a body portion having upstanding portions angularly disposed with respect to a transverse plane so as to strengthen said body portion for supporting the weight of an article to be displayed, a prop cut out of said body portion thereby providing an opening where the prop is cut out, said prop being bent rearwardly from the lower upstanding edge of said opening at substantially right angles to the body portion, said opening substantially fitting the article to be displayed whereby the upstanding portion of the body portion below the opening will support the said article in elevated position and said article will engage flatwise against the hinged marginal end of said prop and retain the said prop in said position at substantially right angles to the body portion.

4. A display stand comprising a body portion having upstanding portions angularly disposed with respect to a transverse plane so as to strengthen said body portion for supporting the weight of an article to be displayed, a prop cut out of said body portion thereby providing an opening where the prop is cut out, said prop being bent rearwardly from the lower upstanding edge of said opening at substantially right angles to the body portion, said opening substantially fitting the article to be displayed whereby the upstanding portion of the body portion below the opening will support the said article in elevated position and said article will engage flatwise against the hinged marginal end of said prop and retain the said prop in said position at substantially right angles to the body portion, and a frictional tongue at the opposite end of said opening from said prop whereby said tongue and prop will press against said article toward each other.

5. A display stand comprising a body portion, a prop bent at substantially right angles to said body portion cut from said body portion so as to provide an opening therein for reception of an article to be displayed, and a tongue cut from said prop adapted to be bent out of the plane thereof and rest behind and engage the article being displayed for retaining said article in said opening.
